UNITED STATES PATENT OFFICE.

STERLING H. CAMPBELL, OF ST. LOUIS, MISSOURI, ASSIGNOR TO RAILWAY DEVICES COMPANY, OF ST. LOUIS, MISSOURI, A CORPORATION OF MISSOURI.

COUPLER-RELEASE RIGGING.

Application filed June 13, 1925. Serial No. 36,952.

To all whom it may concern:

Be it known that I, STERLING H. CAMPBELL, a citizen of the United States of America, residing at the city of St. Louis, State of Missouri, United States of America, have invented a certain new and useful Coupler-Release Rigging, of which the following is such a full, clear, and exact description, as will enable any one skilled in the art to which it appertains to make and use the same, reference being had to the accompanying drawings forming part of this specification.

My invention relates to a coupler release rigging and particularly to that type of rigging in which a link having sliding movement in the operating arm engages with the lock pin by means of an open loop.

In the accompanying drawings, which illustrate one form of coupler release rigging made in accordance with my invention, together with a portion of the end of a railway car to which the same is applied, Figure 1 is a front view; Figure 2 is a top plan view; and Figure 3 is an enlarged side view, partly in section.

The end of the car, indicated at 5, is provided with the usual striking block 6 and coupler head 7, the knuckle of the latter being controlled by the lock pin 8. Secured to the end of the car by brackets 9 is a rock shaft 10 provided at its outer end with a downwardly extending handle 16, and at its inner end with a forwardly projecting operating arm 11 terminating in a vertical eye 12. Sliding vertically in the eye 12 is

the body 13 of a link having on its upper end a head 14. The lower end of the link terminates in an open loop 15 in the form of a flat spiral, that is, a spiral all parts of which lie in a single plane. This form of loop permits the link being engaged with the eye of the lock pin when the rock shaft 10 is removed from the car but prevents the removal of the link from the eye when the parts are in position on the car. In order that the device may function properly to prevent the accidental disengagement of the link from the pin eye the loop 15 should extend through appreciably more than a complete revolution, as shown in Figure 1.

Having fully described my invention, what I claim as new and desire to secure by Letters Patent of the United States is:

1. In a device of the class described, the combination with an operating arm, of a lock pin provided with an eye, and a connector having sliding connection with the arm and terminating at its lower end in an open loop in the form of a flat spiral engaging the eye.

2. In a device of the class described, the combination with an operating arm, of a lock pin provided with an eye, and a connector having sliding connection with the arm and terminating at its lower end in an open loop in the form of a flat spiral extending through more than a complete revolution and engaging the eye.

In testimony whereof, I have hereunto set my hand this the 11th day of June, 1925.

STERLING H. CAMPBELL.
